keepsie, N.Y., a corporation of Delaware
No Drawing. Filed July 15, 1958, Ser. No. 748,608
5 Claims. (Cl. 167—55)

This invention relates to an improved preparation and method for obtaining relief from coughing in human beings.

It is an object of the present invention to provide a preparation and method of the above character which gives both immediate and also relatively long-range relief from coughing.

The coughing reflex is generally caused by the stimulus of irritation of the mucous membrane of the respiratory tree resulting from colds and other upper respiratory infections, allergies, and foreign bodies or irritants. Cough relief preparations, such as syrups and cough drops, which are commonly available, contain topical agents to soothe and relieve the irritation of the mucous membrane and are effective only while the soothing action is taking place. In the case of a persistent irritation, the coughing accordingly resumes as soon as the topical agent disappears from the affected membrane. As a result, cough preparations of this type which depend upon the action of topicals remedies do not afford sustained relief from coughing.

Recognizing this situation, attempts have heretofore been made to obtain more long-range relief by using sedatives and narcotics, such as chloroform or codeine. These preparations are not satisfactory since the sedatives and narcotics are habit-forming and have undesirable side effects or do not adequately suppress the coughing reflex when administered in safe unit dosage quantities.

It is an object of the present invention to overcome the difficulties and disadvantages heretofore encountered, and to provide an improved preparation and method for obtaining relief from coughing, which will not only afford immediate relief from coughs resulting from irritations of the mucous membrane but will also suppress the coughing reflex for a relatively prolonged period of time so as to give sustained relief from coughing.

A further object is the provision of an improved preparation and method of the above character for relief from coughing which will not have undesirable side effects upon either the central nervous system or other organs of the patient.

In accordance with one aspect of our invention, we provide a suitable vehicle either in liquid form, such as a syrup, or in solid form, such as a lozenge or cough drop, which includes a topical or local agent for soothing or pacifying the mucous membrane which will afford immediate relief from the irritation while in contact therewith; and which also includes an improved anti-tussive agent operating upon the central and peripheral action centers for coughs of the nervous system of the patient to suppress the response to the irritation and control the cough reflex.

The vehicle employed may, of course, be varied considerably. Where the preparation is to be supplied in liquid form, the vehicle should include a suitable solvent which is non-toxic to a human being and which is compatible with the other ingredients employed. For this purpose, we may employ water, ethyl alcohol, glycerine, sorbitol, propylene glycol, or various alkaline or acidified mixtures thereof.

Mixed with the solvent are suitable flavoring and coloring materials and a topical or local agent for soothing and pacifying the mucous membrane. In many instances, the flavoring materials serve also as topical agents which

2

will soothe the mucous membrane. Thus, sugar and various fruit extracts, such as cherry, orange, lemon, or lime extract, serve both as flavoring materials and as soothing agents. Other topical soothing agents, such as glycerine, sorbitol, propylene glycol, or various syrups such as simple syrup, white pine syrup, or fruit syrup may also be added. In this connection, various non-toxic nauseants, and expectorants such as ammonium chloride, potassium guaiacolsulfonate, ipecacuanha, tartar emetic, squills, ammonium carbonate, and iodides of various alkalies, may be added, which serve as topical or local agents since they stimulate the flow of bronchial secretion, which in turn serves to soothe the mucous membrane.

Other active or flavoring materials, such as citric acid or other organic acids, amines or their salts, such as lemon-orange glycerides (bio-flavonoid), ascorbic acid and caramel, may be added.

The coloring materials employed should be edible and non-toxic and compatible with the other ingredients and for this purpose, we may employ such coloring agents as brilliant blue, amaranth, charcoal and certified food coloring, such as orange No. 7, red No. 2, etc.

The proportions of these ingredients, serving as flavoring, coloring, and soothing agents in the carrying vehicle, are not critical. Thus, the flavoring material should be proportioned to taste and the coloring material to appearance. Sufficient soothing agents should be employed so as to give topical or local relief to the irritation of the mucous membrane, when administered in reasonable dosage units. The quantity of solvent employed should be sufficient so that the syrup or liquid preparation will readily flow without adhering unduly to the surfaces of the container, spoons, and other utensils and at the same time maintaining a sufficiently concentrated solution to permit the soothing agent to adhere to the irritated portions of the mucous membrane.

The percentage of water and other solvents, including any of the alcohols, may be varied between approximately 20 percent and 99 percent by weight of the complete preparation. These percentages are to include and solvent used in the flavoring extracts and also any water combined with sugar or oxygen derivatives used in the preparation of this kind of syrup. The percentage of sugar or other oxygen derivatives when used may be varied between approximately 5 percent and 79 percent by weight, and the percentage of other soothing agents when used between approximately 0.2 percent and 15 percent by weight. Other flavoring materials may be added in quantities to suit the taste, and coloring materials may be added in quantities to obtain the desired appearance.

As previously indicated, we add to the mixture of carrying vehicles and other ingredients an anti-tussive agent operating upon the central and peripheral action centers for coughs of the nervous system to suppress the response to the irritation and to control the cough reflex. For this purpose, we employ an improved anti-tussive agent in the form of certain indole alkaloid extracts of plants of the genus *Rauwolfia* and also of the genus *Gelsemium* and possible other sources from succulent plants such as *yucca*, fungi, etc. together with their salts and also synthetic and natural reproductions thereof of the type which will act upon the central and peripheral action centers for coughs of the nervous system to suppress the response to the irritation and to control the cough reflex and at the same time will not cause undesirable side effects on the central nervous system or on the other organs of the body nor cause the release of serotonin by the body tissue. We have found that the following indole alkaloid extracts of *Rauwolfia* and *Gelsemium* may be employed:

(1) The indole alkaloids which are yellow colored, strong anhydronium bases and the salts thereof. These bases are characterized by being of aromatic ionic form

and having a pK_a of between 10.4 and 11. Representative of this group of indole alkaloids are serpentine, serpentine, alstonine, and sempervirine. Serpentine, serpentine, and alstonine may be obtained as natural extracts of the genus *Rauwolfia*; and serpentine and sempervirine may also be obtained as extracts of plants of the genus *Gelsemium*. A particularly satisfactory anti-tussive agent is serpentine with an empirical formula of $C_{21}H_{20}O_3N_2$ and with a structural formula of:

(2) Tertiary indole alkaloids in which ring E is heterocyclic. Representative of this group of indole alkaloids are reserpine, isoreserpine, aricine, tetrahydroserpentine, and δ -yohimbine. Reserpine is a particularly satisfactory anti-tussive agent and has an empirical formula of $C_{22}H_{26}O_4N_2$ and a structural formula of:

The usefulness of tertiary indole alkaloids seems to be enhanced where ring E is highly hydroxylated. An example of a tertiary indole alkaloid of this type is isoraunesine. All of the tertiary indole alkaloids indicated above are extracts of plants of the genus *Rauwolfia*.

In addition to the indole alkaloids listed above under 1 and 2, we may also employ the non-toxic compatible salts, such as the nitrate, chloride, acetate and other organic or inorganic salts. The salts may be prepared either by reacting the acid with the alkaloid or by double decomposition with other salts. In addition to using the natural indole alkaloid extracts of *Rauwolfia* and *Gelsemium* and the salts thereof, we may employ synthetic and natural reproductions thereof.

While all of the above-indicated indole alkaloids may be employed, we prefer to employ serpentine and the salts of serpentine and more particularly we prefer to employ serpentine nitrate. We have found that very satisfactory anti-tussive effects are obtained from preparations containing serpentine nitrate without any undesirable side effects or toxicity and without the release of serotonin by the body tissue.

The anti-tussive agent is mixed with the other ingredients in the preparation. The proportion of the anti-tussive agent can, of course, be varied. However, we have found that desirable anti-tussive effects are obtained by administering unit dosages of the indicated alkaloids of between 0.01 mg. and 0.1 mg. Accordingly, the percentage of anti-tussive agent in the liquid preparation should be controlled so that the indicated quantity is present in the desired unit dosage of the preparation. Generally speaking, the desired unit dosage will be a teaspoonful or tablespoonful and the quantity or percentage can be readily computed. In a preparation having ingredients of the type indicated above, we have found that between 0.00015 and 0.0015 percent by weight of the anti-tussive agents will supply the desired quantity thereof in unit dosages of one teaspoonful.

Specific examples of liquid preparations, such as cough syrups, embodying our invention are as follows:

Example I

The following ingredients were thoroughly mixed together to produce a liquid preparation for relief from coughing, which soothes the mucous membrane of the respiratory tree and also operates on the central and peripheral action centers for coughs of the nervous system to suppress the cough reflex.

	Approximate percentage or parts by weight
Ingredients:	
Water	31.726482
Ethyl alcohol	4.0
Sugars (sucrose, dextrose, levulose)	60.0
Wild cherry extract	3.51
Citric acid	0.715
Ammonium chloride	0.0286
Caramel	0.0143
Amaranth	0.004
Brilliant blue	0.000118
Serpentine nitrate	0.0015

After the ingredients are thoroughly mixed together, the preparation is ready to be orally administered to a human being. In this connection, the proportions are such that in unit dosages of one teaspoonful (approximately 5.0 cc.), approximately 0.09 mg. of the anti-tussive agent will be present and will provide the desired effect upon the central and peripheral action centers for coughs of the nervous system. Thus, the liquid cough preparation will provide both immediate and relatively long-range relief from coughing.

The preparation may be suitably packaged and may be stored for relatively long periods of time for later use without deterioration.

It will be appreciated that the percentages of ingredients may be varied within the ranges indicated above and that other vehicles, flavoring, coloring and topical agents may be substituted for the ones specifically listed. Thus, the percentage of serpentine nitrate may be varied between 0.00015 and 0.0015 percent by weight of the mixture. In addition, other indole alkaloids and salts thereof of the type indicated, which are non-toxic and do not cause the release of serotonin, may be substituted for the serpentine nitrate.

Example II

The following ingredients were thoroughly mixed together to produce a liquid preparation for relief from coughing, which soothes the mucous membrane of the respiratory tree and also operates on the central and peripheral action centers for cough of the nervous system to suppress the cough reflex.

	Approximate percentage or parts by weight
Ingredients:	
Water	31.127182
Ethyl alcohol	4.0
Sugar (sucrose, dextrose, levulose)	58.6
Wild cherry extract	3.51
Citric acid	0.715
Ammonium chloride	0.0286
Caramel	0.0143
Amaranth	0.004
Brilliant blue	0.000118
Reserpine	0.0008
Glycerine	2.0

After the ingredients are thoroughly mixed together, the preparation is ready to be orally administered to a human being. In this connection, the proportions are such that in unit dosages of one teaspoonful (approximately 5.0 cc.), approximately 0.05 mg. of the anti-tussive agent will be present and will provide the desired effect upon the central and peripheral action centers for coughs of the nervous system. Thus, the liquid cough preparation

will provide both immediate and relatively long-range relief from coughing.

The preparation may be suitably packaged and may be stored for relatively long periods of time for later use without deterioration.

It will be appreciated that the percentages of ingredients may be varied within the ranges indicated above and that other vehicles, flavoring, coloring, and topical agents may be substituted for the ones specifically listed. Thus, the percentage of reserpine may be varied between 0.00015 and 0.0015 percent by weight of the mixture. In addition, other indole alkaloids and salts thereof of the type indicated, which are non-toxic and do not cause the release of serotonin, may be substituted for the reserpine.

Liquid preparations indicated in the above examples are particularly intended for oral administration. In addition, liquid preparations may be provided for direct hypodermic injection into the blood stream. For this purpose, only a liquid vehicle, such as water, physiological saline solution, or the like is mixed with the anti-tussive agent of the above type. The proportion of anti-tussive agent to liquid may be varied but should be such that in conventional injection dosages, between 0.01 and 0.1 mg. of the anti-tussive agent are present. We have found that satisfactory results are obtained by utilizing unit injection dosages containing approximately 0.05 mg. per unit dosage.

As previously indicated, our improved preparation for relief from coughing may also be provided in solid form, such as a tablet, lozenge, or cough drop. In preparing tablets or cough drops, standard hard candy-making procedures or cold-press tabletting processes may be followed.

A cough drop should contain a suitable carrying vehicle, flavoring materials, coloring materials if desired, a topical or local soothing agent, and an anti-tussive agent of the above-indicated type, which operates upon the central and peripheral action centers for coughs of the nervous system. Sugar serves satisfactorily as a vehicle or carrying agent, as well as a flavoring agent. Various other flavoring agents, such as fruit extracts of the type indicated above, namely, cherry, orange, lemon or lime extract, licorice, and citric acid may also be added. Caramel may also be used both as a coloring and flavoring agent, and other coloring agents, such as amaranth, brilliant blue, charcoal and certified food coloring may be used also. The sugar and the other flavoring agents serve satisfactorily as topical soothing agents, and other soothing agents may also be added, such as glycerine, ammonium chloride, potassium guaiacolsulfonate, sorbitol, propylene glycol, and the like.

A concentrated syrup is prepared from the sugar and it is cooked to a temperature of between 265° and 350° F. It is then partially cooled to a temperature of between 200° and 250° F. and the other ingredients, including an anti-tussive agent of the type indicated above which operates upon the central and peripheral action centers for coughs of the nervous system to suppress the cough reflex, are mixed therewith. The percentage of ingredients may be considerably varied, but we have found that satisfactory results are obtained by using between 97 percent and 98 percent by weight of sugars and between 1 and 2 percent by weight of other soothing agents where employed. Other flavoring materials may be added in quantities to suit the taste, and the coloring materials are added in quantities to obtain the desired appearance. Sufficient anti-tussive agent of the type indicated should be added so as to provide between 0.01 and 0.1 mg., preferably 0.05 mg., in each dosage unit or cough drop.

We have found that where cough drops of the conventional size are prepared, the desired results are obtained by adding between 0.0005 and 0.005 percent by weight of the anti-tussive agent to the mixture.

The partially cooled mixture is then poured into molds to provide cough drops of the desired size and shape.

A specific example of one method of making a cough drop embodying our invention is as follows:

Example III

5 A concentrated sugar syrup is prepared and is heated to a temperature of approximately 265° to 326° F. Thereafter, it is cooled to a temperature of approximately 210° F., and the following ingredients are added thereto in the indicated proportions.

10	Ingredients:	Percent by weight of total mixture
	Licorice -----	0.4
	Charcoal -----	0.8
	Essential oils -----	0.25
	Serpentine nitrate -----	0.0025

15 After the ingredients have been thoroughly mixed, the mixture is then cooled and formed into cough drops of approximately 2.16 grams in weight. The cough drops thus prepared each contain approximately 0.05 mg. of serpentine nitrate. When administered orally, the cough drops give topical relief by soothing the mucous membrane of the respiratory tree and they also operate upon the central and peripheral action centers for coughs of the nervous system to suppress the cough reflex.

20 It should be understood that other flavoring, coloring, and topical agents may be substituted for those indicated in this example and that the percentage of ingredients may be varied as indicated.

25 In addition, other anti-tussive agents operating upon the central and peripheral action centers for coughs of the nervous system of the type indicated above, which will not cause undesirable side effects and which will not cause the release of serotonin, may be substituted for serpentine nitrate and the percentage of anti-tussive agent may be varied within limits so that each cough drop has between 0.01 and 0.1 mg.

30 In addition to cough drops prepared by standard candy-making procedure, we may provide tablets prepared by cold-press tabletting methods. A suitable binding material, such as starch, is employed; and sugar, flavoring materials, and topical agents may be added if desired, as well as our improved anti-tussive agent. The ingredients are thoroughly mixed together, and sufficient anti-tussive agent is added so that between 0.01 and 0.1 mg. will be present in each tablet. Unit quantities are then cold-pressed into tablets of the desired size.

35 The tablets may be orally administered to give relief from coughing, and the anti-tussive agent will act upon the central and peripheral action centers for coughs of the nervous system to suppress the cough reflex.

40 It will thus be seen that we have provided an improved preparation and method for obtaining relief from coughing, which will give immediate relief by soothing the mucous membrane of the respiratory tree and will also give more long-range relief by operating upon the cough center of the nervous system.

45 Modifications may be made in the illustrated embodiments of our invention. Thus, under certain circumstances, sedatives and narcotics may also be included in our improved preparation and other active and inactive ingredients may also be added if desired.

50 We claim:

55 1. A preparation to be orally administered for obtaining relief from a person's coughing caused by irritations of the mucous membrane of the respiratory tree which comprises a carrying vehicle including a topical remedy for relieving irritations of the mucous membrane and an anti-tussive agent in the form of serpentine nitrate, said preparation being in unit dosage form with each dosage unit containing between 0.01 and 0.1 mg. of serpentine nitrate.

60 2. A preparation to be administered in unit dosage form for relief from a person's coughing which comprises a carrying vehicle having mixed therewith reserpine in

unit dosage quantities of between approximately 0.01 and 0.1 mg.

3. A preparation to be administered in unit dosage form for relief from a person's coughing which comprises a carrying vehicle having mixed therewith an anti-tussive agent selected from the group consisting of alstonine, aricine, reserpinine, isoreserpinine, serpentine, serpentine, tetrahydroserpentine, sempervirine, δ -yohimbine, isoraunicine, the salts thereof and mixtures thereof, said preparation being administered in dosage units containing between approximately 0.01 and 0.1 mg. of said anti-tussive agent.

4. The method for obtaining relief from a person's coughing due to irritation of the respiratory tract which comprises orally administering to said person a preparation which includes a carrying agent and an anti-tussive agent selected from the group consisting of alstonine, aricine, isoreserpinine, reserpinine, serpentine, serpentine, tetrahydroserpentine, sempervirine, δ -yohimbine, isoraunicine, the salts thereof and mixtures thereof, said

preparation being administered in dosage units containing between approximately 0.01 and 0.1 mg. of said anti-tussive agent which operates on the central and peripheral action centers for coughs of the nervous system to suppress the cough reflex but will not cause undesirable side effects nor the release of serotonin by the body tissue.

5. The method for obtaining relief from a person's coughing due to irritation of the respiratory tract which comprises orally administering to said person a preparation which includes a carrying agent and an anti-tussive agent in the form of serpentine nitrate in dosage units of between approximately 0.01 and 0.1 mg.
